FIG. 7. FIG. 19.1.

Patented Sept. 19, 1922.

1,429,850

UNITED STATES PATENT OFFICE.

THOMAS J. DOWD, OF NEW YORK, N. Y.

ADJUSTABLE TAP AND DIE.

Application filed April 11, 1921. Serial No. 460,154.

To all whom it may concern:

Be it known that I, THOMAS J. DOWD, a citizen of the United States, residing at New York city, in the county of New York and State of New York, have invented certain new and useful Improvements in Adjustable Taps and Dies; and I do hereby declare the following to be a full, clear, and exact description of the invention, such as will enable others skilled in the art to which it appertains to make and use the same.

This invention relates to new and useful improvements in adjustable taps and dies and has for its primary object the provision of means whereby screw threads may be easily and accurately formed internally or externally on a pipe or other hollow element.

Another object of this invention is the provision of means for adjusting the internal and external thread cutting elements to permit use of the device on pipes of different diameters.

A further object of this invention is the provision of the external thread cutting elements forming an adjustable connection between the internal thread cutting elements and the holder and which permit approximate adjustment of the internal thread cutting elements to a pipe of a certain diameter.

A further object of this invention is the provision of an adjustable expander whereby the internal thread cutting elements are held against collapsing and also permits adjustment of the latter to the wall of a pipe as desired.

A still further object of this invention is the provision of an adjustable tap and die of the above stated character which will be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:

Figure 1 is a top plan view illustrating an adjustable tap and die constructed in accordance with my invention,

Figure 2 is a side elevation illustrating the same,

Figure 3 is a vertical sectional view illustrating the expander in the act of supporting the internal thread cutting elements, 60

Figure 4 is a sectional view taken on the line 4—4 of Figure 3,

Figure 5 is a side elevation illustrating the expander, 65

Figure 6 is a vertical sectional view illustrating the device adjusted for external work.

Figure 7 is an enlarged vertical sectional view illustrating the device, and 70

Figure 8 is a longitudinal sectional view illustrating the device.

Referring in detail to the drawings, the numeral 1 indicates a holder or block having a central bore 2 and radially extending slots 3 which open outwardly through the outer face of the holder 1 and also communicate with the bore 2. The slots 3 slidably receive die or external thread cutting elements 4 and are retained in said slots by means of 80 set screws 5 which permit said elements to be adjusted inwardly and outwardly of said slots as desired. One of the ends of the elements 4 have formed thereon thread cutting faces 6 while their other ends are provided with openings 7 and the walls of said

openings are arranged angularly in respect to each other so as to prevent rotation of taps or internal thread cutting elements 8. Stems 9 are formed on the elements 8 and 90 have angularly related walls to cooperate with the walls of the openings 7 when inserted in said openings for the purpose of preventing rotation of the elements 8 relative to the elements 4 or the holder 1 during the use of the tool. The outer faces of the elements 8 have formed thereon thread cutting teeth 10 adapted when in engagement with the internal wall of a pipe or the like to cut or form screw threads thereon. 100

The elements 8 are tapered transversely towards their inner faces from their outer faces and received by dove-tailed grooves 11 of an expander 12. The expander 12 consists of an internally screw threaded body 105 13 on which are formed resilient fingers 14 having their opposing side faces beveled and aligned with the walls of the grooves 11 to slidably receive the internal thread cutting elements 8. The inner faces of the fingers 110 14 are provided with screw threads 15 to receive a tapered adjusting screw 16 which is

adapted to expand said fingers when threaded towards the body 13 for the purpose of forcing the elements 8 into engagement with the interior wall of a pipe and to regulate the pressure of said elements against the pipe and consequently vary the depth of the screw threads formed on the wall of the pipe by said elements 8. The set screw 16 at its inner end is provided with a reduced screw threaded extension 17 which is adapted to be received by the screw threaded bore of the body 13 when said adjusting screw has been fully adjusted or moved inwardly towards said body. The fingers 14 of the expander 12 are adapted to assume their normal positions when the set screw 16 is threaded in an outward direction consequently permitting the elements 8 to move in the direction of each other.

20 The use of the device as a tap is as follows:

The internal thread cutting elements 8 are adjusted approximately to the internal diameter of the pipe which is to be threaded by adjusting the elements 4 in the holder 1 and the adjustment of the adjusting screw 16 in the expander. The holder with the ends of the thread cutting elements 8 in contact with the pipe is rotated with a slight pressure thereon and sufficient to advance the thread cutting elements 8 into the pipe as the screw threads are formed on the internal wall thereof. To facilitate the rotation of the body 1, handles 18 are provided which may be formed integrally with the body or if desired detachably secured to the latter in any suitable manner. The expander 12 if desired may be constructed of such a length as to support the thread cutting elements 8 substantially throughout their entire length.

40 To use the device as a die, the thread cutting elements 8 are removed and the elements 4 are positioned in the holder 1 as shown in Figure 6 with their cutting faces 6 in opposing relation. The elements 4 may be adjusted in the slots of the body 1 to position the thread cutting faces 6 against the outer walls of pipes of different diameters. With the elements 4 properly adjusted for operation on a pipe of a certain diameter and by rotating the holder 1 through the medium of the handles 18 and with a slight pressure thereon, screw threads are formed on said pipe.

55 Referring to my modified form of invention, the fingers 14 are bifurcated as shown at 20 from their free ends towards their attached ends and are provided with screw threaded sockets to receive expanding screws 21 which are adapted to expand the bifurcated portions of said fingers laterally to engage the internal thread cutting elements when the latter have been forced outwardly by the adjusting screw 16. This construction is preferably used when the device

is constructed on a large scale for operation on large size pipes.

It is to be noted that the adjusting screw 16 forms a bed for the internal thread cutting elements to engage and the latter are forced out by said screw during its movement towards the body 13 of the expander.

The expander extends the full length of the internal thread cutting elements 8 and the body thereof has lugs 22 which fit into notches 23 formed in the wall of the opening of the holder 1 to cause the expander to turn with the holder and thereby support the cutting elements throughout their entire lengths and cause them to move with the holder without any danger of twisting.

While I have shown and described the preferred embodiment of my invention, it will be understood that minor changes in construction, combination, and arrangement of parts may be made without departing from the spirit and scope of the invention as claimed.

Having thus described my invention what I claim is:—

90 1. An adjustable tap and die comprising a holder, internal and external thread cutting elements carried by said holder and said external thread cutting elements forming the connection between the internal 95 thread cutting elements and the holder.

2. An adjustable tap and die comprising a holder, die cutters adjustably and detachably secured to the body, and tap cutters carried by said die cutters.

100 3. An adjustable tap and die comprising a holder having a central bore, and radially extending slots communicating with the bore, die cutters adjustably and detachably mounted in said slots, and tap cutters detachably secured to the die cutters and adapted to be adjusted in relation to the body by the adjustment of the die cutters in the slots of the body.

110 4. An adjustable tap and die comprising a holder having a bore and slots communicating therewith, members detachably and adjustably secured in said slots and entering said bore, thread cutting teeth carried by one of the ends of said members, and tap 115 cutters carried by the other ends of said members and capable of being detached therefrom.

120 5. An adjustable tap and die comprising a holder having a bore and slots in communication therewith, members adjustably and detachably mounted in said slots and having formed on one of their ends thread cutting faces, tap cutters detachably secured to the other ends of said members and an expander 125 for said tap cutters.

130 6. An adjustable tap and die comprising a holder having a bore and slots communicating therewith, members adjustably and detachably mounted in said slots and hav-

ing at one of their ends thread cutting faces and their other ends provided with openings with angularly related walls, tap cutters, stems formed on said tap cutters and having 5 angularly related walls and received by said openings, and means for expanding and contracting the tap cutters.

7. An adjustable tap and die comprising a holder having a bore and slots in communication therewith, members adjustably and 10 detachably mounted in said slots and having thread cutting faces at one of their ends, tap cutters detachably secured to the other ends of said members, a body having grooves 15 receiving said tap cutters, resilient fingers carried by said body and spaced to receive the tap cutters, and means for expanding said fingers and tap cutters.

8. An adjustable tap and die comprising 20 a holder having a bore and slots in communication therewith, members adjustably and detachably mounted in said slots and having thread cutting faces at one of their ends, tap cutters detachably secured to the other 25 ends of said members and having tapered side faces, a body having dove-tailed grooves receiving said tap cutters, resilient fingers

formed on said body and relatively spaced and having their side walls in alignment with the walls of said grooves and beveled 30 towards their inner faces to receive the tap cutters, screw threads formed on the inner faces of said fingers, and a wedge-shaped adjusting screw threaded in said fingers for expanding the latter and for moving the 35 tap cutters to fit pipes of different internal diameters.

9. An adjustable tap and die comprising a holder, die cutters adjustably mounted on 40 said holder, tap cutters carried by the die cutters, an expander body having grooves to receive the tap cutters, bifurcated fingers formed on said body and receiving the tap cutters therebetween, an adjusting screw threaded to and between said fingers and 45 engaging the tap cutters for forcing the latter outwardly, and set screws for expanding the bifurcated portions of the fingers against the tap cutters.

In testimony whereof I affix my signature 50 in presence of a witness.

THOMAS J. DOWD.

Witness:

BENNETT S. JONES.
